UNITED STATES PATENT OFFICE.

LUCY A. BURGHARDT AND WILLIAM G. ROGERS, OF DENVER, COLORADO.

CHILD'S FOLDING CARRIAGE.

SPECIFICATION forming part of Letters Patent No. 632,671, dated September 5, 1899.

Application filed May 22, 1899. Serial No. 717,684. (No model.)

To all whom it may concern:

Be it known that we, LUCY A. BURGHARDT and WILLIAM G. ROGERS, citizens of the United States of America, residing at Denver, 5 in the county of Arapahoe and State of Colorado, have invented certain new and useful Improvements in Children's Folding Carriages; and we do declare the following to be a full, clear, and exact description of the invention, such as will enable others skilled in the art to which it appertains to make and use the same, reference being had to the accompanying drawings, and to the letters and figures of reference marked thereon, which 10 form a part of this specification.

Our invention relates to improvements in folding carriages or carts for children, our object being to provide a construction of this class which when not in use may be folded 20 and made to occupy but little space, whereby it may be conveniently carried about in street-cars and vehicles, and which may be quickly unfolded and put in position for use.

Our further object is to provide a folding carriage which shall be simple in construction, comparatively economical in cost, reliable, durable, and efficient in use.

To these ends the invention consists of the features, arrangements, and combinations 30 hereinafter described and claimed, all of which will be fully understood by reference to the accompanying drawings, in which is illustrated an embodiment thereof.

In the drawings, Figure 1 is a perspective view of our improved folding cart or carriage. Fig. 2 is a vertical longitudinal section taken through the same. Fig. 3 is a vertical cross-section taken in front of the wheels, looking rearward. Fig. 4 shows the carriage in the 40 folded position and on a larger scale. Fig. 5 is a top detail view of the bracket which connects the journal with the body of the carriage, the journal and pivoted brace being also shown.

Similar reference characters indicating corresponding parts in the views, let the numeral 5 designate the body of the carriage, which comprises a bottom part 5^a, sides 5^c, hinged to the bottom part, as shown at 6, and the ends 5^d and 5^e, also hinged to the bottom part. In the rear bottom part of the carriage is located the seat 7, which is composed of a top 7^a and

two ends 7^c and 7^d. The end 7^d is hinged to the bottom of the carriage, as shown at 7^h. The ends 7^c and 7^d are hinged to the top 7^a, 55 as shown at A and B. The bottom of the end 7^c is located between two blocks C, attached to the bottom, and which may be lifted from this position and drawn forward, when the seat by virtue of its hinged joints will 60 straighten out and lie flat in the bottom of the carriage. This may be considered the first step in folding the body of the carriage.

To each edge of the bottom, near its forward extremity, is pivoted, as shown at 8, a 65 bar 9. These bars embrace and support the sides of the carriage when the latter is in use. To each bar 9 near its rear extremity is pivoted, as shown at 10, a hand-bar 12. The bars 12 are connected at their rear extremities by 70 a cross-bar 13. The two draw-bars 9 and the bars 12 on each side are made practically rigid when in use by means of a keeper 14 slidingly mounted on the bar 12 and adapted to slip over the rear end of the bar 9, which extends beyond the pivot 10.

The body of the carriage is supported by two wheels mounted on stub-journals 17, which are entirely independent of each other. To each of these journals is rigidly attached 80 a bracket 18, composed of two inclined arms 18^a, one extending forwardly and the other rearwardly. The lower extremities of these arms merge into a stirrup-shaped socket 18^c, in which the portion of the journal which is 85 inside the wheel is located. The stirrup of the bracket is rigidly secured to the journal. The upper extremities of the bracket-arms are hooked into the apertured depending ends of metal straps 19, secured to the bottom of 90 the carriage-body in such a manner that the bracket extremities turn freely in the straps to permit the wheel to fold inwardly beneath the body of the carriage when not in use, as shown in Fig. 4.

When the carriage is in use, each wheel 15 is held in the operative position by means of a brace 20, whose lower extremity is pivotally attached to the journal 17 between the bracket-arms, its upper extremity terminating in an eye 20^a, adapted to slip over a pin 21, attached to the bottom of the carriage-body. This brace holds the wheels in position for use. When, however, it is desired

to fold the carriage, the eye extremity of the brace is slipped from the pin 21 and the brace turned on its pivot 20° to a position parallel with and engaging one of the bracket-arms 18^a.

To prevent the body of the carriage from tipping, its rear portion is provided with a support composed of two laterally-inclined arms 22 and a forwardly-inclined arm 23. The arms 22 merge into a rod 24, whose lower extremity engages the ground or other surface. The upper extremities of the arms 22 and 23 are hooked into eyes 24, secured to the bottom of the carriage. The upper extremity of the arm 23 terminates in a horizontal pin 23^a, whereby the arm is readily detachable from its eye to permit the supporting device to fold forwardly. The lower extremity of the arm 23 is arranged to turn in a clasp or collar 27, surrounding the lower extremities of the arms 22, whereby when the upper extremity of the arm 23 is detached the arm may be swung around to occupy a position parallel with and engaging one of the arms 22. The forward extremities of the carriage sides are each provided with a hook 25, adapted to engage an eye 26 in the front end of the carriage, whereby the latter is supported in position for use. In order to fold the carriage-body, the hooks 30 are detached from their engaging eyes.

The draw-bar arms 9 are connected at the rear of the carriage-body by a transverse arm 9^a, which supports the rear end of the carriage in position for use, preventing it from turning backward on its hinges.

In order to fold the carriage to the position shown in Fig. 4, the forward end of the seat 7 is raised from its stop-blocks and pulled forward, causing it to occupy a flat position 40 in the bottom of the carriage. The ends 5^d and 5^e are then folded toward each other and laid down parallel with the bottom 5^a, after which the sides are folded inwardly and down upon the ends. Each sliding keeper 14 is 45 then moved rearwardly on its bar 12 sufficiently to disengage it from the rear extremity of the bar 9. The handle-bars 12 are then turned upward and forward until the cross-bar 13 occupies a position immediately in front of the front end of the carriage. The keepers 14 are then slipped over the forward extremities of the bars 9, which are then dropped to a horizontal position. The upper extremities of the braces 20 are then detached 55 and swung around against one of the bracket-arms 18, allowing the wheels to fold inwardly beneath the bottom of the carriage-body.

The depending extremities of the metal straps 19 are longer on one side of the carriage than on the other in order to allow the wheel on the corresponding side to fold to a horizontal position after the wheel on the opposite side has been folded.

Having thus described our invention, what 65 we claim is—

1. In a cart or carriage, the combination with the body portion, of supporting-wheels

adapted to fold inwardly beneath the body of the carriage, draw-bars pivoted to the carriage-bottom on opposite sides and embracing the sides of the carriage, two hand-bars pivotally connected with the draw-bars, and movable keepers adapted to lock the draw-bars and hand-bars together, making them longitudinally rigid.

2. In a folding cart or carriage, the combination of the folding body part, wheels upon which the body is mounted, said wheels being arranged to fold inwardly to a horizontal position beneath the bottom of the carriage-body, draw-bars pivoted to the carriage-bottom on opposite sides and embracing the sides of the carriage, two hand-bars pivotally connected with the draw-bars, and movable keepers adapted to lock the draw-bars and hand-bars together.

3. The combination of the folding body, the jointed extensible seat, the wheels arranged to fold inwardly, draw-bars pivoted to the carriage-bottom on opposite sides and embracing the sides of the carriage, hand-bars pivotally connected with the draw-bars, and movable keepers adapted to lock the draw-bars and hand-bars together.

4. The combination of the folding body, comprising the bottom, the sides and ends hinged to the bottom and arranged to fold inwardly, draw-bars pivoted to the carriage-bottom on opposite sides and embracing the sides of the carriage, two hand-bars pivotally connected with the draw-bars, and movable keepers adapted to lock the draw-bars and hand-bars together, making them longitudinally rigid.

5. In a folding carriage, the combination with the folding body, of the draw-bars having their forward extremities pivoted to the bottom of the carriage, hand-bars respectively pivoted to the draw-bars near the rear extremities of the latter, sliding keepers mounted on the hand-bars and adapted to slide over the rear extremities of the draw-bars, and a cross-bar connecting the rear extremities of the hand-bars.

6. In a folding carriage, the combination of the folding body part, the wheels, two independent journals upon which the wheels are mounted, means for connecting each journal with the carriage-body, the arrangement being such that the wheels are allowed to fold inwardly beneath the bottom of the carriage, draw-bars pivoted to the carriage-bottom on opposite sides and embracing the sides of the carriage, hand-bars pivotally connected with the draw-bars and movable keepers arranged to lock the draw-bars and hand-bars together.

7. In a folding carriage, the combination of the folding body, the wheels, independent journals upon which the wheels are mounted, and means for connecting each journal with the carriage-body, the arrangement being such that the wheels are allowed to fold inwardly beneath the bottom of the carriage,

said means comprising a bracket to which each journal is rigidly secured, and a brace pivotally attached to each journal at one extremity, its opposite extremity having an eye, 5 and a pin attached to the bottom of the carriage and arranged to receive the eye of the brace when the carriage is in position for use.

8. In a folding carriage, the combination of the folding body, the wheels, two independent journals upon which the wheels are mounted, a bracket rigidly attached to each journal, and comprising a forwardly and a rearwardly extending arm, said arms being pivotally attached to the carriage-bottom to allow the 15 wheels to fold inwardly, and an inwardly-extending brace whose lower extremity is pivoted to the journal, its upper extremity being detachably connected with the carriage-body and arranged, when its upper extremity 20 is detached, to swing on its lower pivot to a position against and parallel with one of the bracket-arms.

9. A folding carriage comprising a folding body, two folding wheels, and a folding support for the rear extremity of the carriage 25 comprising two laterally-inclined arms whose upper extremities are hinged to the bottom of

the carriage, and a forwardly-inclined arm whose upper extremity is detachably connected with the carriage, while its lower extremity is movably connected with the lateral arms, whereby, when its upper extremity is detached, it may be swung around to a position parallel with and engaging one of the lateral arms, allowing the support to be folded 30 35 against the carriage-bottom.

10. The combination of a carriage-body, the wheels, independent journals upon which the wheels are mounted, a bracket attached to each journal, each bracket comprising a forwardly and a rearwardly extending arm, depending metal straps attached to the carriage-body and to which the bracket-arms are hinged, the said straps being longer on one 40 45 side of the carriage than the other to allow both wheels to fold to a horizontal position.

In testimony whereof we affix our signatures in presence of two witnesses.
